UNITED STATES PATENT OFFICE.

WILLIAM PICK, OF NEW YORK, N. Y.

AUTOMATIC TRAIN-CONTROL MECHANISM.

1,087,823.

Specification of Letters Patent. Patented Feb. 17, 1914.

Application filed January 15, 1913. Serial No. 742,291.

To all whom it may concern:

Be it known that I, WILLIAM PICK, a citizen of the United States, residing at New York, in the county of New York and 5 State of New York, have invented certain new and useful Improvements in Automatic Train-Control Mechanism, of which the following is a specification.

This invention comprehends means for automatically stopping a train should the engineer pass a danger signal, and relates more particularly to that type of train control mechanism wherein signal operated means engage and operate means carried upon a 15 locomotive, to apply the brakes and cut off the steam.

The primary object of the invention resides in the provision of mechanism of this nature which shall be of extremely simple 20 construction, which will be very efficient in operation, and which will effectually stop a locomotive should the same run by a signal set at danger.

With these and other objects in view, as 25 will become more apparent as the description proceeds, the invention consists in certain novel features of construction, combination, and arrangement of parts, as will be hereinafter described and claimed.

30 For a complete understanding of my invention, reference is to be had to the following description and accompanying drawings, in which,

Figure 1 is a side elevation of a locomotive embodying my invention, the signal operated means being shown in the position for operating the mechanism carried by the locomotive, Fig. 2 is a top plan view of the signal operated portion of my invention, 35 Fig. 3 is a section taken upon the plane of line 3—3 of Fig. 2, Fig. 4 is a section taken upon the plane of line 4—4 of Fig. 2, and, Fig. 5 is a side elevation of a signal of the semaphore type adapted to be used in connection with my invention.

In the following description and accompanying drawings similar parts will be referred to and designated by like characters of reference.

50 Referring in detail to the drawings by numerals, 5 designates the track rails and 6 supporting ties therefor. A casing 7 is supported upon certain of the ties and is formed with a depending portion 8 adjacent one of its ends, which extends below the level of the upper surfaces of said ties,

as clearly shown in Fig. 3. A wedge-shaped tongue 9 is pivotally secured at one end within the casing 7 by means of the horizontal pivot 10. The top of the casing is slotted as at 11 to permit the tongue to be projected upwardly and the bottom of the casing is slotted, as at 12, to permit the tongue to drop below the level of the rail treads.

A wedge 13 slides within the depending portion 8 of the casing and is adapted to engage the bottom edge of the tongue 9 to project said tongue through the slot 11. The wedge is connected by means of a rod 13^a to a bell-crank 14, which may be actuated by a 70 rod 15. The rod 15 is movable vertically by means of a semaphore signal 16. When the signal is set at danger, the rod 15 is elevated and the wedge 13 moved so as to project the tongue 9 through the slot 11. 75

The tongue 9 is formed upon its lower edge with the spaced ears 9' between which the wedge 13 is adapted to project. The wedge is formed with a slot 13' parallel to its inclined face, through which a pin 9'' projects. This pin is secured within the ears 9', thus connecting the wedge and tongue to each other. It will be noted that this construction limits the movement of the wedge and also prevents the tongue from 85 becoming displaced.

The locomotive 17 has pivotally secured thereto a bell-crank 18, one end of which is rigid with a depending arm 19. The other end of the bell-crank is connected to the 90 rack bar 20 which is connected, by arms 21, to an air valve 22 and a steam valve 23. Pipes 24 and 25 conduct steam into the steam chest 26 through the valve 23. Pipes 27 and 28 lead compressed air from the tank 95 29 to the cylinder 30 for the purpose of actuating the brakes. A depending arm 31 has a spring-pressed pawl 32 pivoted thereon for engagement with the teeth of the rack bar 20. The pawl locks the bar 20 against 100 movement in one direction but may be released from engagement therewith by means of the flexible connection 33.

When the semaphore is set to indicate danger, the tongue 9 is in its raised position, 105 at which time it extends within the path of the arm 19. When the locomotive passes over this tongue the arm 19 is swung rearwardly and upwardly, causing the valves 22 and 23 to be actuated so as to set the 110 air brakes and cut off steam from the cylinder. It will thus be seen that the locomotive

is automatically brought to a stop after having run by a danger signal.

From the foregoing description in connection with the accompanying drawings, it will be seen that I have provided a very simple and reliable automatic means for stopping a train should the engineer disregard a danger signal.

It is to be understood that while I have shown and described the preferred embodiment of my invention, I do not wish to be limited to this exact construction, combination, and arrangement of parts, but may make such changes as will fall within the spirit and scope of the invention.

Having thus described my invention, what I claim is:—

1. In a device of the character described, the combination with a locomotive, of valves through which the steam and compressed air flow, arms connected to said valves, a rack bar pivotally connected to said arms, a pawl engaging said rack bar to lock the same against movement in one direction, a bell-crank lever connected at one of its ends with said rack bar, and a depending arm

rigid with said bell-crank lever for engagement with an obstacle.

2. In a device of the character described, the combination with a locomotive, of valves through which steam and compressed air flow, depending arms for actuating the valves whereby the air brakes may be set and the flow of steam through the cylinder cut off, a horizontal rack bar pivotally connected to the lower extremities of the arms and supported thereby, a pawl engaging the rack bar and locking it against movement in one direction, a pivoted bell-crank lever connected at the extremity of one of its arms to the rack bar, and an arm depending from the other extremity of the bell-crank lever for engagement with an obstacle, whereby the rack bar is moved longitudinally and the valves actuated.

In testimony whereof I affix my signature in presence of two witnesses.

WILLIAM PICK.
